Specification for Design.

Patented May 7, 1918.

Application filed June 25, 1915. Serial No. 36,408. Term of patent 14 years.

To all whom it may concern:

Be it known that I, OSCAR F. FORSBERG, a citizen of the United States, residing at Yonkers, in the county of Westchester and State of New York, have invented a new, original, and ornamental Design for Desk Telephone-Stands, of which the following is a specification, reference being had to the accompanying drawing, forming part thereof.

In the drawing, Figure 1 is a plan view, and Fig. 2 is a perspective view of a desk telephone stand showing my new design.

What is claimed is:

The ornamental design for a desk telephone stand, as shown.

In witness whereof, I hereunto subscribe my name this 23rd day of June, 1915.

OSCAR F. FORSBERG.
